UNITED STATES PATENT OFFICE.

SAMUEL BETTIGOLE, OF NEW HAVEN, CONNECTICUT.

CANDLESTICK.

1,012,973.

Specification of Letters Patent. Patented Dec. 26, 1911.

Application filed March 20, 1911. Serial No. 615,793.

To all whom it may concern:

Be it known that I, SAMUEL BETTIGOLE, a citizen of the United States, residing at New Haven, in the county of New Haven 5 and State of Connecticut, have invented a new and useful Improvement in Candlesticks; and I do hereby declare the following, when taken in connection with the accompanying drawings and the letters of 10 reference marked thereon, to be a full, clear, and exact description of the same, and which said drawings constitute part of this specification, and represent, in—

Figure 1 a side view of a candle-holder 15 constructed in accordance with my invention. Fig. 2 a vertical sectional view of the candle-holder head. Fig. 3 a top or plan view of the holder, with the cap removed. Fig. 4 an underside view of one of the slides, 20 detached.

This invention relates to an improvement in candle-sticks or candle-holders, the object being to provide means for firmly supporting a candle and extinguishing the same 25 when it burns down to the top of the candle-holder; and the invention consists in the construction hereinafter described and particularly recited in the claims.

In illustrating my invention, I employ a 30 candle-stick 2 which may be of any approved design and may be a single stick or a candelabrum. In the head 3 of the candle-holder is a transverse groove or slot 4 in which slides 5 and 6 are arranged to move 35 transversely. At the center of their adjacent ends these slides are formed with downwardly projecting fingers 7 which, when the candle burns down, will come together and snuff the wick. Mounted in the 40 head are levers 8 and 9 pivotally connected at their inner ends to the respective slides. Between them is arranged a spring 10 the tendency of which is to separate the outer 45 ends of the fingers and force the inner ends of the slides together. These levers may be operated in any desired manner and may preferably and as herein shown, have finger- 50 pieces 11 which extend down through slots 12 in the head. If desired the top of the candle-holder will be surmounted by a cap-

plate 13 which covers the ends of the slides and the ends of the levers.

To insert the candle into the socket 14 the slides are separated and the candle placed between them, and these slides will 55 hold and firmly support any size of candle up to the limits of the size of the socket. When the candle burns down to the socket or to a point just below the slides 5 and 6, the spring 10 will force the slides inward 60 and extinguish the flame.

Instead of forming the head of the candlestick integral with the body or base 2, it may be formed separately and provided with a plug 15, as shown in Fig. 2 of the 65 drawings, which plug is adapted to be entered into any candle-holder and permits one of the candles of the candelabrum to be removed if it is desired to do so temporarily.

I claim:—

1. The combination with a candle-holder having a head with a candle-receiving socket, of two transverse slides arranged within the head and each formed with centrally arranged fingers extending downwardly into the said socket, levers mounted in said head and engaged with said slides whereby the said slides may be moved, and a spring tending to force the inner ends of 75 the slides together. 80

2. The combination with a candle-holder having a head formed with a candle-receiving socket and with a transverse groove, of two slides arranged within said groove and each formed at their inner ends with fingers 85 projecting downward into said socket, two levers pivotally mounted in the head and having engagement with said slides, said levers formed at their outer ends with finger-pieces, a spring between the levers and 90 tending to force the inner ends of the levers and slides together, and a cap-plate secured to said head over said slide.

In testimony whereof, I have signed this specification in the presence of two subscribing witnesses.

SAMUEL BETTIGOLE.
